Attorney.

UNITED STATES PATENT OFFICE.

JOHN W. PECKHAM, OF PARKSTON, SOUTH DAKOTA.

STEREOTYPE-CASTING FRAME.

1,423,146.

Specification of Letters Patent.

Patented July 18, 1922.

Application filed April 29, 1921. Serial No. 465,596.

To all whom it may concern:

Be it known that I, JOHN W. PECKHAM, a citizen of the United States, residing at Parkston, in the county of Hutchinson and State of South Dakota, have invented a certain new and useful Improvement in Stereotype-Casting Frames, of which the following is a full, clear, and exact description.

10 The object of this invention is to provide a device for casting type-high stereotypes without the use of a special machine.

Printers of newspapers and the like periodicals are in the habit of obtaining what is known as "mat" service wherein stereotype matrices are furnished to them from which they may make stereotypes for the purpose of printing the subjects of said matrices in their periodicals.

20 Various machines have been devised for casting such stereotypes, but all such machines with which I am familiar, are of more or less complicated construction, and because of their price, are not available to printers of newspapers and periodicals of small circulation, such as those printed in rural districts.

To the end that the job or other small printer may take advantage of the mat service above mentioned, without the necessity of providing himself with a casting machine, I have devised a frame for casting type-high stereotypes, this frame being of simple and inexpensive construction and capable of being used upon an ordinary job press, so that when the press is adjusted to printing position, the platen and bed thereof will form sides for said frame, and thereby provide a mold cavity into which type metal may be poured upon a mat to form a type-high stereotype.

To this end the invention comprises a frame having top and bottom members and end members, the top and bottom members being grooved upon their inner faces at intervals throughout their length, said grooves being adapted to receive complementary tongues upon the ends of adjustable intermediate members adapted to form within said frame a mold cavity of such dimensions as to provide a stereotype that will fit within the space in a form or galley provided for it, the top member of such frame being detachably connected to the end members thereof so that when the

frame is positioned for casting this top member may be removed for the purpose of allowing the molten type metal to be poured into such mold cavity, all as I will proceed now to explain and finally claim. 60

In the accompanying drawings illustrating the invention, in the several figures of which like parts are similarly designated, Figure 1 is a perspective view of the casting frame. Fig. 2 is an enlarged fragmentary perspective view illustrating the arrangement and relative sizes of the top or bottom member and the intermediate members. Fig. 3 is a fragmentary detail showing the method of attaching the top member 70 to the end members.

The frame comprises a bottom member 1 and similar end members 2 and 3, suitably secured to the bottom member to form a rigid frame. Attached to the end members 2 and 3 by means of slot and tongue joints 4 is the top member 5, this top member being removably connected to the frame by means of pins 6 or the like passing through the slot and tongue joints 4. 80

The top and bottom members are formed preferably of type-high brass rule, eighteen points or one-quarter of an inch in thickness, and their inner faces are provided at regular intervals throughout their length 85 with grooves 7, these grooves being preferably six points or one-half pica or one-twelfth of an inch in width and depth. In the preferred form of my invention these grooves are spaced apart two picas, or one-third of an inch, from the face of one to the corresponding face of the next, thereby leaving a space between grooves of one end one-half picas. The grooves in the top member are arranged in the same relative position 90 to the ends of the frame as the grooves in the bottom member, so that lines passing from top to bottom of the frame through corresponding grooves in the top and bottom members will lie in parallelism with 100 each other and with the ends of the frame.

In order that a space may be blocked off within the frame, of such dimensions as will provide a stereotype of the proper size to fit the space provided for it in a form, 105 I utilize intermediate members 8 and 9. Each of these members is provided at its ends with tongues 10 of dimensions corresponding to the dimensions of the grooves 7 and adapted to fit therein as shown. The 110

intermediate member 8 is formed of type-high brass, one pica or one-sixth of an inch in thickness, and the intermediate member 9 is formed of type-high brass, one and one-half picas, or one-fourth of an inch in thickness, and the tongues of each of these members are arranged so that one of their faces lies in the plane of the side of the member, thus leaving, in the member 8, a projecting portion at the side of the tongue of one-half pica, or one-twelfth of an inch, and on the member 9, of one pica, or one-sixth of an inch. It will thus be seen that the combined thickness of those portions of the intermediate members not included in the width of their tongues, is one and one-half picas, or the total space between grooves. Therefore by proper arrangement of the intermediate members 8 and 9, and by turning them face for face or not as is necessary or desirable, any measurement may be had for the space between them in units of two picas, picas and half picas. Thus, for example, a person desiring to cast a stereotype cut twenty-five ems wide can do so by inserting the members 8 and 9 in grooves in the top and bottom members a distance equal to twenty-five ems apart to form the box or casting space between the two members. If then he wishes to make the space twenty-five and a half ems wide, this can be done by changing the member 8 side for side. Thus any measure desired can be obtained by a proper manipulation of these two intermediate members.

As one method of forming type-high stereotypes by the use of my frame I will describe the procedure followed when the frame is used with an ordinary job press, which method is substantially as follows: The operator first removes the grippers, and removes the tympan from the platen of the press, thus leaving both bed and platen bare. He then applies a fresh tympan of clean white paper and inserts under the lower tympan bail a piece of thin brass rule to act as a support for the casting frame to rest upon when the tympan is moved to impression position. Then one side of the casting frame is inked and placed with that side against the tympan and with the bottom member 1 resting against the support. Then the inking rollers and disk are removed from the press and it is operated through a printing revolution. If the impression made by the frame upon the tympan is not even and uniform, the press is moved to impression position and the impression screws are adjusted until an even clear impression of the frame is made upon the tympan. Then the frame and tympan are removed, again leaving the bed and platen of the press bare. The intermediate members of the frame are inserted in the desired position and the frame again placed upon the platen resting

against the support, a piece of thin type-high brass rule, preferably four points in thickness, cut to the proper length, is placed within the mold cavity formed by the intermediate members and resting upon the bottom member so as to prevent the subsequently poured metal from entering the grooves 7, and the press again moved to impression position. Next the top member is removed, by withdrawing the pins 6 and raising the top member off of the end members. Meanwhile, the type metal has been heated to such a temperature that it will turn white paper brown but will not burn it, and this metal is then poured into the mold cavity and allowed to stand thus for approximately five minutes to heat the parts. While this heating is taking place, the mat should be prepared in the usual way, by warming and sprinkling its face lightly with French chalk and brushing off the chalk with soft cotton. A tail piece long enough to extend above the top of the press bed should be pasted to the end of the mat.

At the expiration of the heating period the press is backed up and the slug of metal removed; then the intermediate members and the top member are replaced in position and the mat is inserted beneath the frame with its back resting upon the platen and its face toward the mold cavity and the press is run forward again to impression position and metal poured in as before. After the metal has cooled sufficiently the press is again backed up and the casting taken out. It will be found that this casting is a type-high solid metal stereotype, and the only things remaining to be done to it to prepare it for use are the sawing off of the tail piece, planing down of the edges, and routing out of any high spots.

If it is desired to economize in type metal, a wooden block, shaped to the proper size for the finished cut; and less than type high, may be inserted in the mold cavity and wedged therein so as to prevent it from falling forward against the mat, and the metal poured in as before. When a plain block of wood is used, the cut must be nailed upon it after it is finished, but if it is desired to dispense with this nailing, I may provide the face of the block of wood with undercut grooves substantially as shown in the patent of Frank H. Aiken No. 121,036, dated November 21, 1871, into which the metal may run during the casting operation. It will be understood that the end members of the casting frame must be of greater height than the bed and platen of the press upon which it is to be used. This is necessary in order that the mold cavity may have sides extending above the platen and bed of the press to provide a pouring space for the metal. For example, I propose to use a frame having top and bottom members substan-

tially eleven inches long and end members substantially nine inches long for the ordinary seven by ten job press, and for larger presses the frame would be of correspondingly greater dimensions.

The top and bottom bars may be provided with a scale of figures; and pins 6 may be chained or otherwise secured to the top bar or elsewhere for preventing their loss.

10 Although my frame is herein described as for use particularly upon a job press or the like, I contemplate using it also upon any sort of casting bed, such, for example, as those beds upon which stereotypes are ordinarily cast.

15 I have herein described a specific embodiment of the frame of my invention, and have designated materials and dimensions, but it is to be understood that changes may be 20 made in such details without departing from the spirit of the invention or the scope of the following claims.

What I claim is:—

25 1. A stereotype casting frame, comprising a top member, a bottom member, end members, and intermediate members, said top and bottom members being grooved upon their inner faces at equidistant intervals throughout their length, and said intermediate members provided with tongues at their opposite ends adapted to engage said grooves, whereby by adjusting said intermediate members relative to each other with their tongues engaging corresponding 30 grooves in said top and bottom members, a rectangular mold space will be formed between said intermediate members and top and bottom members.

35 2. A stereotype casting frame, comprising a top member, a bottom member, and end members, said top and bottom members being grooved at equidistant intervals throughout the length of their inner faces, and intermediate members provided at their ends 40 with tongues of dimensions corresponding to the dimensions of said grooves and adapted to be positioned between said top and bottom members with their tongues engaging said grooves to form a mold cavity within 45 said frame.

50 3. A stereotype casting frame, comprising bottom and end members and a top member, said bottom and top members being provided upon their inner faces throughout their 55 length with grooves spaced at equal distances apart in units of printers' measure, and intermediate members having their ends formed with tongues of dimensions corresponding to the dimensions of said grooves 60 and adapted to fit therein, one face of said

tongues lying in the plane of the face of said members and the other face thereof being set in from the opposite face of said members, whereby by turning said intermediate members face for face in said frame 65 the width of the space formed between the said intermediate members may be varied.

4. A stereotype casting frame, comprising a top member and a bottom member and end members connecting same, said top and bottom members provided with grooves spaced at equal distances apart throughout the length of said members, said spaces being in units of printers' measure or multiples thereof, and a pair of intermediate members provided at their ends with tongues of dimensions equal to the dimensions of said grooves and adapted to fit therein to form a mold space within said frame, one of said members being of greater thickness than the other and the tongues of said members being so arranged thereon that by manipulation of said members the space formed between them may be enlarged or diminished in units or fractions of units of printers' measure.

5. A stereotype casting frame comprising top and bottom members and end members, said top and bottom members being grooved upon their inner faces throughout their length, said grooves being spaced at a distance of two picas apart relative to corresponding faces thereof, and being one-half pica in width and depth, and a pair of intermediate members provided at their ends with tongues of dimensions equal to the dimensions of said grooves and adapted to fit therein to form between them a mold cavity within said frame, said intermediate members being respectively one pica and one and one-half picas in thickness and having their tongues so arranged that by turning them face for face with respect to each other, the space between them may be increased or diminished in multiples of half picas.

6. A stereotype casting frame, comprising a top member, a bottom member, and intermediate members, means on the inner faces of said top and bottom members and on the ends of said intermediate members whereby said intermediate members may be arranged within the frame formed by said top and bottom and end members to form a mold cavity, said top member being removable for the purpose of filling said cavity with metal.

In testimony whereof I have hereunto set my hand this 26th day of April A. D. 1921.

JOHN W. PECKHAM.
